UNITED STATES PATENT OFFICE.

HARRY FERDINAND LEISSNER, OF LJUSNE, SWEDEN.

CENTRIFUGAL GOVERNOR.

1,260,922.

Specification of Letters Patent. Patented Mar. 26, 1918.

Original application filed June 29, 1916, Serial No. 106,722. Divided and this application filed January 18, 1917. Serial No. 143,178.

To all whom it may concern:

Be it known that I, HARRY FERDINAND LEISSNER, a citizen of the Kingdom of Sweden, residing at Ljusne, Sweden, have invented a new and useful Improved Centrifugal Governor, of which the following is a specification.

This invention being a division of my co-pending patent application Serial Number 106,722 relates to centrifugal governors and more particularly to centrifugal governors adapted for use in combination with speed regulating devices, in which an adjustment of the centrifugal governor for various speeds, while working, is desired.

Various constructions have been proposed in order to bring about such a centrifugal governor. In certain cases the centrifugal governor has been provided with a loading 20 spring which is compressed more or less according to the speed desired. The intermediate members necessary for the transmission of power from said spring to the fly-balls, have, however, rendered the construction of the governor too complicated, and owing thereto the use of such centrifugal governors as well as of such regulating devices is rather limited.

The object of this invention is the provision of a centrifugal governor adapted to work for two or more different ranges of speed without necessitating the use of any regulating means.

With this object in view the centrifugal 35 governor is provided with a spring load consisting of two or more springs of different strength, each of said springs operating within its separate range of speed.

A preferred embodiment of a centrifugal 40 governor constructed according to this invention is illustrated in the accompanying drawing, in which—

Figure 1 is a diagrammatic representation 45 of a centrifugal governor provided with springs of the above named kind and of the connections between the governor and the member to be controlled. Fig. 2 is a sectional view of a spring device actuating the fly-balls of the governor and having two 50 springs.

Referring to Fig. 2 the spring load of the governor comprises a helical spring 1 provided at the one end with a hook 2, by means of which the spring may be attached to one fly-ball 12 of a centrifugal governor. At the 55 other end the spring 1 is screwed onto a cylindrical member 3 having outer threads at the one end and formed at the other end as a sleeve 4 closed by a cover 5. Placed in the center of the cover 5 is a recess into which 60 the end of the hook 2 is generally inserted. On account thereof, the tension of the spring 1 may be adjusted by turning the member 3 in relation to the spring. Located inside the sleeve 4 is another spring 6 of less strength 65 than the spring 1 and bearing, at the one end, against the bottom of the sleeve 4 and, at the other end, against a nut 7 formed as a piston and adapted to move in the sleeve 4. Screwed into the nut 7 is a rod 8, which 70 may be connected with the governor sleeve 13 movable along the governor shaft 13'. The nut 7 is provided with a pin 9 secured to the same and entering a longitudinal slot 10 in the sleeve 4, so that the nut is prevented from turning, but is able to move in the sleeve on turning the rod 8. Secured between the bottom of the sleeve 4 and the nut 7 is a tube 11 surrounding the rod 8 and serving to limit the compression of the 80 spring 6. The length of the tube 11 in relation to the strength of the springs 1 and 6 is so chosen, that on pulling, at the one side, at the hook 2 and, at the other side, at the rod 8 the spring 1 cannot be extended, ere 85 the nut 7 bears against the tube 11.

As will appear from Fig. 1, such a spring device is provided between each fly-ball 12 and the movable governor sleeve 13. By turning the member 3 of each spring device 90 the tension of the corresponding spring 1 is so adjusted, that it corresponds to a maximal speed desired of the machine in question and by screwing the rod 8 outward or inward the tension of the spring 6 is so 95 adjusted, that it corresponds to the minimal speed desired of the machine.

The connection between the governor and the member to be controlled may for instance be effected in the manner shown diagram- 100

matically in Fig. 1. The governor sleeve 13 is by means of links 14, 15, 16 connected with said member. In the present case this member is supposed to be a main supply valve, 5 the quite closed position of which is indicated by the line A, while the quite open position of the valve is indicated by the line B. The path of movement of the valve is indicated by the vertical line C. The link 10 15 is at the center connected with a hand lever 17 pivotally mounted on the stationary shaft 18. In Fig. 1 three different positions of the fly-balls and of the hand lever are shown. Said positions are indicated by I, 15 II and III. Concerning the fly-balls, I designates their lowest position, II their highest position at the minimal speed of the machine, and III their highest position at the maximal speed of the machine. As to the 20 hand lever 17, the position I corresponds to the stop position of the machine, the position II corresponds to the running of the machine at the lowest speed, and III to its running at the highest speed.

25 The device operates as follows: When the hand lever 17 is in the stop position I, the link-system 14—16 occupies the position designated by I, the fly-balls are in their lowest position I, and the supply valve is in its 30 closed position B. If the hand lever be moved to the position II, this will have no influence on the fly-balls, and therefore the link 14 will remain in its position I, whereas the links 15 and 16 are moved to the position II^a. Owing thereto, the valve is fully 35 opened, and the machine is started. According as the speed increases, the fly-balls 12 are raised, while the spring 6 is compressed. At the same time the link-system 40 14—16 is turned around the center (II) of the link 15 in such a manner, that the supply valve closes successively, according as the fly-balls are raised. When the fly-balls reach the position II, the link-system occupies the position II^b in which the supply 45 valve is closed. Thus the supply may vary between a quite open and a closed position, while the fly-balls are moving between the positions I and II. In the position II of 50 the fly-balls the spring 6 is compressed to such an extent, that the nut 7 bears against the tube 11.

If the greater speed is to be used, the hand lever 17 is reversed to the position III. At 55 the beginning the fly-balls cannot pass the position II, and therefore the link-system occupies, after the reversal, the position III^a, in which the supply valve is quite open. This position is maintained, until the speed 60 of the machine is increased to such an extent, that the tension of the spring 1 is exceeded by the fly-balls. If the speed be further increased and the fly-balls begin to

rise while extending the spring 1, the supply valve will be throttled successively, 65 since the link-system 14—16 is turned about the center (III) of the link 15. When the fly-balls 12 reach the highest position III, the link-system 14—16 occupies the position III^b in which the supply valve is closed 70 entirely. Thus the supply may vary between the fully open and the closed position, while the fly-balls are moving between the positions II and III.

Obviously, the number of springs operating consecutively may be chosen at will greater than two in correspondence to the 75 number of different speeds of the machine for which the governor is to be adjusted. The different springs need not be placed one 80 inside another, as in the drawing, but may be located on a line or beside another, though the disposal described above, as saving room, is to be preferred.

Having now described my invention, what 85 I claim as new and desire to secure by Letters Patent is:

1. A centrifugal governor having a spring load comprising a number of helical springs of different strength, means for securing the 90 springs between the fly balls and the sleeve of the governor, and means whereby a weaker spring is set out of action before a stronger spring is brought in action.

2. A centrifugal governor, having a spring 95 load comprising two helical springs of different strength disposed one inside the other, means for securing the springs between the fly balls and the sleeve of the governor and means whereby the weaker spring is set out 100 of action before the stronger spring is brought in action.

3. A centrifugal governor having a spring load comprising a number of helical springs of different strength, means for securing the 105 springs between the fly balls and the sleeve of the governor, means for adjusting the tension of the springs, and means whereby a weaker spring is set out of action before a stronger spring is brought in action. 110

4. A centrifugal governor having a spring load comprising a sleeve and two helical springs of different strength disposed inside and outside of said sleeve respectively, means for connecting the outer spring to the 115 fly ball of the governor, a movable member within said sleeve adapted to compress the said inner spring and connected to the sleeve of the governor, and means within said first-mentioned sleeve whereby the said 120 inner spring is set out of action when compressed to a certain extent.

5. A centrifugal governor having a spring load comprising a strong helical spring formed with a hook at one end thereof engaging the fly ball of the governor, a sleeve 125

surrounded by said spring, a threaded portion on said sleeve engaged by said spring, a cover at one end of said sleeve having a central recess engaged by the said hook, a weak helical spring within said sleeve, a longitudinally movable nut in said sleeve bearing against said weak spring, a screw

threaded rod engaging said nut and connected to the sleeve of the governor, and a tube within the said weak spring to limit 10 the compression thereof.

In testimony whereof I have signed my name.

HARRY FERDINAND LEISSNER.
